UNITED STATES PATENT OFFICE.

HENRY J. EDLUND, OF BURLINGTON, VERMONT.

BROOM.

1,208,522.

Specification of Letters Patent. Patented Dec. 12, 1916.

Application filed May 5, 1916. Serial No. 95,577.

To all whom it may concern:

Be it known that I, HENRY J. EDLUND, a citizen of the United States, and a resident of Burlington, in the county of Chittenden and State of Vermont, have invented a new and Improved Broom, of which the following is a full, clear, and exact description.

This invention relates to brooms and particularly to an improved construction which is simple and strong while utilizing a minimum amount of broom corn or other similar material.

Another object in view is to provide a broom with a rigid socket, part of the socket firmly clamping the broom corn and part acting as a bracing member for causing the free ends of the broom corn to bow in a comparatively wide circle.

A still further object in view is to provide a metallic clamping member provided with means for securing the same to a handle and formed with a clamping groove for gripping broom corn near the end, these members being associated with a flaring mouth for the clamping member so as to allow a free easy bending of the corn with a minimum bending at the point where the broom corn is clamped in position.

In the accompanying drawings, Figure 1 is a perspective view of a broom embodying the invention, part of the handle being broken away. Fig. 2 is an edge view of the structure shown in Fig. 1. Fig. 3 is a longitudinal vertical section through Fig. 1 on line 3—3. Fig. 4 is a section through Fig. 2 on line 4—4.

Referring to the accompanying drawing by numerals, 1 indicates a handle of any desired kind which may be secured to what may be termed the head 2 in any suitable way, as for instance, by rivets 3, the handle 1 fitting into a tubular section 4 of head 2. In forming the head 2 the same is preferably made from two pieces of sheet metal 45 and connected together so that the division line 5 therebetween will be at the edges, though this is not absolutely necessary, as it allows the parts to be secured together by rivets 6 and also by rivets 7, rivets 6 passing through a suitable connecting bar 8. In forming the head 2 the same conforms in general outline to the head or socket member of the construction disclosed in my co-pending application Serial No. 65,154, filed 55 December 4, 1915, but is changed somewhat in order to secure the broom body 9 rigidly

to the head without using a separate clamping band and separate head.

As shown more particularly in Fig. 1, the plates of which the head 2 is formed are 60 pressed out so as to provide suitable reinforcing beads or raised portions 9 and also raised portions 10. Adjacent the raised portions 10 is a depressed portion 11 which acts as a bracing fin whereby all the parts are 65 comparatively rigid when the rivets have been properly placed in position. At a desirable point, preferably near the tubular member 4, is provided with a grooved de- 70 pression 12 made so as to entirely encircle 75 the end of the body 2 and to firmly clamp the broom straws of said body 2 in position, as shown more particularly in Fig. 3. Suitable rivets or other clamping members 13 extend through the two plates and the broom 75 corn at the groove 12 so as to hold the same properly in position. This groove is preferably depressed sufficiently and held in the depressed position in such a manner as to cause the broom corn clamped to be rigid 80 and immovable at that place.

As shown more particularly in Fig. 3, the head 2 extends from the groove 12 an appreciable distance toward the sweeping end 85 of the body 2 and at the extreme edge is provided with a bell or flare 14 against which the straw presses when the broom is in use and the straw is bent to one side. By this construction and arrangement a gradual bend or bowing is provided between the bell 90 or point 14 and the clamping depressed section or groove 12. If the body 2 was cut off adjacent the groove 12 the straws would attempt to bend at the point where they are clamped rigidly together and would consequently break so that the broom would, in a short time, become valueless for the purpose intended. However, by arranging the flared or bell section 14 an appreciable distance 95 away from the groove 12 the straws are allowed to flex or bend freely and to bow between the bell 14 and the groove 12, said bowing action causing practically no movement at the groove section 12, thus negating any tendency to break at that point. 100

What I claim is:

1. In a device of the character described, a head, a broom body having one end extending into said head, said head being formed with an annular depressed portion 110 acting on the head for causing the same to rigidly clamp the broom body, said head

overlapping the broom body to an appreciable extent so as to produce flexing of the broom body at a point distant from the place where the broom body is clamped and 5 rivets extending through said broom body and the depressed portion of said head.

2. In a device of the character described, a broom body, a socket member therefor provided with a depressed portion or groove 10 extending entirely therearound, rivets for holding said depressed portion or groove in proper position, said rivets passing through said broom body adjacent one end and said depressed portion pinching said broom body 15 adjacent said end, said socket member extending an appreciable distance from said depressed portion toward the free end of the broom so as to present a spaced flared member, means extending from said socket for 20 receiving an operating handle, and bracing members extending from said socket member and merging into the means for receiving said handle.

3. In a device of the character described, 25 a broom body, a head for said broom body formed from a plurality of plates of sheet metal pressed out for producing a socket portion and a handle receiving portion, said

handle receiving portion having a pair of bracing members and said socket receiving portion being provided with a flared section and a depressed annular section for gripping the end of said broom body.

4. In a device of the character described, a broom body and a head therefor provided 35 with a socket portion and a handle receiving portion, said body being formed from a pair of plates pressed out for producing said socket portion and said handle receiving portion, rivets extending through certain parts 40 of said plates for holding the same rigidly together, said socket portion having an annular depressed section for pinching one end of said broom body in said socket portion, means engaging said depressed section for 45 holding the same properly in position for rigidly gripping said broom body, and a flared section arranged adjacent the outer edge of said socket portion for causing the broom body to have a gradual bend in opera- 50 tion.

HENRY J. EDLUND.
